UNITED STATES PATENT OFFICE.

CHARLES C. MYERS AND HOWARD T. MARING, OF GETTYSBURG, PENNSYLVANIA.

NUT-LOCK.

1,165,800.

Specification of Letters Patent.

Patented Dec. 28, 1915.

Application filed September 1, 1915. Serial No. 43,465.

To all whom it may concern:

Be it known that we, CHARLES O. MYERS and HOWARD T. MARING, citizens of the United States, residing at Gettysburg, in the county of Adams and State of Pennsylvania, have invented certain new and useful Improvements in Nut-Locks, of which the following is a specification.

This invention comprehends certain new and useful improvements in nut locks, and relates particularly to improvements on the type of nut lock for which Letters Patent of the United States, No. 1,142,607, were issued to us June 8, 1915.

As in the already issued patent, the present invention has for its primary object a simple, durable and efficient construction of device of this character which may be used effectively not only in connection with splice bars, fish plates, angle bars, spreader or gage bars, or rail joints generally, but for structural bridge work, machinery, and other metal work, as well as for work which consists partly or wholly of wood and, in fact, in any place where it is desired to prevent the nut from working loose on account of the jars or the like to which it is subjected in service.

A further object of the invention is an improved device of this kind, the parts of which are so constructed and arranged that the device may be applied to any bolt and nut, and without mutilating the threads of either of them, the device being further so constructed and arranged that the nut may be released whenever it is desired to remove the same and the bolt which it holds. And the invention also aims to generally improve devices of this kind so as to render them more useful and commercially desirable.

With these and other objects in view, as will more fully appear as the description proceeds, the invention consists in certain constructions, arrangements and combinations of the parts that I shall hereinafter fully describe and claim.

For a full understanding of the invention, reference is to be had to the following description and accompanying drawing, in which—

Figure 1 is a perspective view showing our nut lock applied to a rail. Fig. 2 is a fragmentary sectional view, the section being taken approximately on the line 2—2 of Fig. 1. Fig. 3 is a detail view of the two parts of the device separated from each other, and Fig. 4 is a fragmentary sectional

view illustrating another application of the device hereinafter specifically referred to.

Corresponding and like parts are referred to in the following description and designated in all of the views of the accompanying drawing by like reference characters.

Referring to the drawing, the numeral 1 designates a bolt of any desired or conventional design or type, the same being shown in that embodiment of the invention illustrated in Fig. 1, as extending through a rail 2, and the fish plates or angle bars 3 which are applied to opposite faces of the rail.

4 designates the nut which may have any desired number of sides and may be of any suitable size, or design, according to the work for which it is required.

The improved nut locking device of this present invention includes a base plate 5, which is preferably formed of spring steel or any other desirable substance or material of the requisite strength and tenacity, and which is formed within its margin with an opening 6, whereby it may be slipped over upon the threaded end of the bolt 1. On one edge the base plate 5 is formed with a preferably pliable flange 7, which is designed to extend over and engage the nut 4 as will be hereinafter more fully described, said flange being preferably formed in two sections divided by a V-shaped slot or notch 8, whereby, as will be clearly understood, the entire flange may be bent over to engage the adjoining side of the nut or the notch 8 receive one corner of the nut whereby the side walls of the slot or notch 8 will engage two sides of the nut, the latter being securely held against turning in either event. It will, of course, be understood, that the number of sides and the size of the nut will govern the practice as to whether or not the entire flange will engage the nut or merely the two sections thereof, which are defined by the intermediate notch 8.

Co-acting with the base plate 5 is a washer 9 which is also formed with an opening 10 whereby it may be slipped upon the threaded end of the bolt 1, before the nut 4 is applied thereto, said washer being preferably bowed, as shown, and being formed of spring steel or similar substance or material, whereby it will at all times exert a pressure against the nut and thereby co-act with the base plate 5 in preventing the nut from turning. It is to be particularly noted that the washer 9 is formed on one edge with a flange

11 which in the applied position of the parts is disposed opposite to the flange 7 hereinbefore referred to and which, when the parts are arranged as illustrated in Fig. 1, is intended to engage the base of the fish plate, whereby it will be prevented from turning and to also engage the adjoining edge of the base plate 5, whereby all liability of the parts being turned will be precluded.

10 It is to be understood that our invention is not limited for use in connection with fish plates, angle bars, and the like. For example, as illustrated in Fig. 4, it may be used in connection with the block or bar 15 which is bolted between the rails at a frog or the like, said bar being designated by the numeral 12. When the parts are applied to this device, the flange 11 not only engages the adjoining edge of the base plate 5, but 20 is designed to extend over one side of the bar 12 whereby it will be securely held from turning.

It is further to be understood, that when 25 the device is used in connection with work which consists of wood, the flange 11 will be embedded in the wood, whereby it will be prevented from turning.

In the practical operation or use of our 30 improved nut lock, the base plate 5 and washer 9 are applied to the threaded end of the bolt, before the nut 4 is applied to the latter, and after the nut has been 35 screwed up to the desired extent, the flange 7, is engaged therewith, as clearly illustrated in the drawing.

Preferably the washer 9 is formed at one 40 side with a split or slot communicating with the opening 10 and at one side of this slot, as best illustrated in Figs. 1 and 3, the metal is turned outwardly. By this construction and arrangement of the parts the 45 washer 9 has greatly increased spring property and will stand great pressure without breaking down and without losing its function or purpose as a spring. Hence it will 50 be seen that by this construction all wear on the nut or other parts and the expansion of the bolt will be taken up and compensated for, all rattling prevented and the nut will be securely held in position as long as desired.

While the accompanying drawing illustrates what we believe to be the preferred 55 embodiment of our invention, it is to be understood that the invention is not limited thereto, but that various changes may be made in the construction, arrangement and proportion of the parts without departing from the scope of the invention as defined in 60 the appended claims.

What is claimed, is:

1. A nut lock comprising a base plate formed with an opening by which it is

adapted to be slipped over the threaded portion of a bolt and provided at one edge with 65 a pliable flange formed intermediate of its ends with a V-notch, and a bowed washer formed of resilient substance and having an opening by which it is also adapted to be slipped over the bolt with one edge of the 70 washer inserted underneath the flange of the base plate and held therein, the other edge of the washer being formed with a flange adapted to engage the adjoining edge of the base plate, as and for the purpose set forth. 75

2. A nut lock, comprising a base plate formed with an opening by which it is adapted to be slipped over the threaded end of a bolt, said base plate being provided at one end with a flange for engagement with 80 the nut, and a washer provided with an opening whereby it may also be slipped over the bolt, said washer being designed to have one edge received underneath the flange and being provided at its other edge with a 85 flange engageable with the adjoining edge of the base plate, and to be embedded in the work when made of wood.

3. The combination with a bolt and nut screwed thereon, of a base plate formed 90 with an opening through which the bolt extends, said base plate being located back of the nut and formed with an outwardly and returned flange engaging the nut, and a bowed washer of spring material mounted 95 upon the bolt back of the nut, one edge of said washer extending behind the flange and engaged thereby and the other edge of the washer being formed with an inturned flange engaging the adjoining edge of the 100 base plate, and the work.

4. The combination with a bolt and nut screwed thereon, of a base plate formed with an opening through which the bolt extends, said base plate being located back of 105 the nut and formed with an outwardly and returned flange engaging the nut, and a bowed washer of spring material mounted upon the bolt back of the nut, one edge of 110 said washer extending behind the flange and engaged thereby and the other edge of the washer being formed with an inturned flange engaging the adjoining edge of the base plate and the work, said washer being formed at one side with a slot and the metal at one side of the slot being turned outwardly to form a spring tongue whereby increased resilience will be imparted to the 115 washer to a maximum degree.

In testimony whereof we affix our signatures in the presence of two witnesses.

CHARLES O. MYERS.
HOWARD T. MARING.
